OVERSEAMING SEWING-MACHINE.

1,133,012.

Specification of Letters Patent. Patented Mar. 23, 1915.

Application filed January 2, 1913. Serial No. 739,724.

To all whom it may concern:

Be it known that we, GEORGE M. EAMES and JOHN S. FINCH, citizens of the United States, residing at Bridgeport, in the county 5 of Fairfield and State of Connecticut, have invented certain new and useful Improvements in Overseaming Sewing-Machines, of which the following is a specification, reference being had therein to the accompanying 10 drawings.

This invention relates to improvements in overseaming sewing machines, and particularly to that class of machines employing two loop-takers in connection with a single 15 needle capable of lateral movements of a comparatively wide range, and has for its object to provide improved means for controlling the movements of the needle in different planes.

20 Referring to the drawings, Figure 1 is a view in front side elevation of an overseaming sewing machine equipped with the present invention, Fig. 2 a top plan view of Fig. 1, Fig. 3 an underside view of the bed-plate 25 shown in the previous figures, Fig. 4 a view in front end elevation of Figs. 1 and 2, Fig. 5 a plan view of the loop-takers, throat or needle plate, feed-dog, and a portion of the bed-plate, Fig. 6 a view representing details 30 later to be referred to, Fig. 7 a perspective view of the arm bracket face-plate, and Fig. 8 a view of the reverse sides of a fabric stitched on the present machine.

1 represents the bed-plate of the sewing 35 machine, upon which is mounted the bracket arm comprising the arm standard 2 and arm bracket 3, 4 the main or needle-bar-driving shaft carrying at its rear end the hand or band wheel 5 and at its opposite end the 40 usual take-up cam 6 for actuating the take-up lever 7, the front face of said cam being provided with a stud bearing 8 upon which is pivoted one end of a needle-bar-actuating link 9.

45 10 represents the needle-bar gate mounted to oscillate on pintle screws, as 11, threaded into the head 12 of the arm bracket 3, and at its front edge provided with bearing hubs 13 and 14 and extension 15, the latter operatively connected through the needle-bar gate connection 16 with the adjustable slide 17 carried by the oscillating lever 18 provided with a downwardly extended bearing shaft 19, which latter is mounted to oscillate in a 50 suitable bearing formed in the bracket 20

secured by screws, as 21, to the rear side of the arm bracket 3, the forward end of said oscillating lever being provided with a hollow downwardly extended portion 23 in which is pivotally mounted the stem 24 60 (shown in dotted lines only, Fig. 2) of the cam follower 25, which latter tracks cam grooves, as 26, of the switch cam 27 carried by the main shaft 4, whereby lateral movements are transmitted from the main shaft 65 to the gate 10.

In the bearing hub 13 is journaled a needle-bar bearing 28 provided at its upper end with a pinion 29, its opposite end being threaded to accommodate adjusting nuts, as 70 30, which latter, in connection with said pinion, act to hold the bearing against endwise movement in the hub 13, said bearing being provided with a keyway 31 which coacts with a key 32 carried by the needle-bar 33 to 75 hold the latter against axial movement independently of the movements of the bearing 28.

34 represents a tubular bearing member 80 which is mounted to move vertically in a suitable bearing formed in the hub 14, and in which is mounted to move axially the needle-bar 33, collars 35 and 36 suitably secured on said needle-bar acting to transmit to the latter vertical movements corresponding to the vertical movements of the tubular bearing, which latter is provided with a stud 37 upon which is fulcrumed the lower end of the link 9, thus vertical movements 85 are transmitted from said main shaft to said 90 needle-bar.

38 represents a spring-depressed cloth-presser-carrying bar provided at its lower end with a cloth-presser 39 and carrying a presser-lifting lug 40 for coacting with a 95 manually operated presser-lifting lever 41', as in earlier constructions.

41 represents a rotating crank shaft mounted in suitable bearings depending from the bed-plate and operatively connected with the main shaft through suitable quartering cranks, as 42, and crank connections, as 43, said crank shaft being provided with a gear 44 which meshes with a gear 45 carried by the loop-taker-actuating shaft 100 46, and as the ratio of said gears is as two to one the shaft 46 is given two rotations to one rotation of the shaft 41, these parts being substantially the same as in all machines of the class referred to herein. 110

47 represents the left hand and 48 the right hand loop-taker, each provided with a suitable thread-holding case, as 49, and a loop-taker shaft, as 50 (one only of which is shown), and to the lower end of each is suitably secured a bevel gear, as 51, which meshes with a like gear 52 carried by the loop-taker-actuating shaft 46, the shafts 50 being journaled in suitable bearings formed 10 in the left and right hand saddles 53 and 54, respectively, adjustably secured to the underside of the bed-plate by suitable screws, as 55.

The means employed for giving to the 15 feed-dog 56 its feed movements and controlling the amplitude of said movements may be of any suitable construction, one form of which is shown in the drawings, but it is not deemed necessary to specifically describe such mechanism, since it is well understood.

57 represents the arm bracket face-plate of usual construction provided with the commonly-employed thread-check 58, thread-tension 59 and thread-controller 60 and secured to the arm bracket head 12 by suitable screws, as 61, threaded into openings, as 62, formed in said head.

63 represents a segment gear pivoted on 30 a bearing stud 64 threaded into the head 12 of the arm bracket, and having pivoted to it, by stud screw 65, one end of a link 66 whose opposite end is pivotally mounted on a stud 67 carried by the adjustable slide 35 block 68 which tracks the under-cut groove 69 formed in the oscillating lever 18, a wing nut 70 acting to hold said slide block in the desired adjustment with respect to the axis of the bearing shaft 19, and said segment gear meshing with the pinion 29.

When employing a single needle in connection with two loop-takers for effecting stitches first at one and then at the opposite side of the median line of vertical movement of the needle, the needle must be given a half turn so that in the formation of each stitch the loop of needle thread will be properly presented to the loop-taker. In the present construction, assuming that the 45 needle openings, as 71, in the throat or needle plate 72 represent the limit of lateral movement of the needle, that the present adjustment of the slide block 17 in the groove 69 of the lever 18 represents the adjustment of the connection 16 to effect lateral movements of the needle corresponding to the distance between said needle openings, and that the axis of the stud 67 connecting the link 66 with the segment gear 50 63 coincides with the axis of the bearing stud 19, the operation of the machine would cause the needle to be aligned first with one and then with the other of said needle openings, and the now stationary segment gear 65 would act on the pinion 29 to give the needle

a half turn, thus effecting a like coöperation of needle and loop-takers, whether at one or the opposite side of the median line of vertical movement of the needle. When it is desired to lessen the amplitude of the lateral movements of the needle, the attendant adjusts the slide block 17 in the direction of the axis of the bearing stud 19, which of itself would negative the means for giving to the needle its half turn, and to overcome this the slide block is adjusted from the axis of the bearing stud 19 a distance sufficient to give to the segment gear such movement as is necessary to compensate for the shortening of the lateral movements of the needle, which form of needle control makes practical the employment of a needle secured concentric with the axis of the needle-bar, and provides adjusting means for changing the amplitude of the lateral movements of said needle.

What we claim is:—

1. In an overseaming sewing machine, the combination with a stitch-forming mechanism including multiple loop-takers, a needle-bar reciprocated in different paths, and a needle carried by said needle-bar and co-operating with each of the loop-takers to form stitches, of means for giving to said needle oscillatory movements about the longitudinal axis of the needle-bar intermediate the different paths of reciprocation of the needle.

2. In an overseaming sewing machine, the combination with a stitch-forming mechanism including multiple loop-takers and a reciprocating needle-bar provided with a needle co-operating with each of the loop-takers to form stitches, of means including coacting gear members for giving to said needle-bar lateral and oscillatory movements intermediate the different reciprocations of the needle.

3. In an overseaming sewing machine, the combination with a stitch-forming mechanism including multiple loop-takers and a reciprocating and laterally movable needle-bar provided with a needle co-operating with each of the loop-takers to form stitches, of means for giving to said needle-bar oscillatory movements including coacting gear members, one of said gear members being controlled to meet changes in the amplitude of said lateral movements.

4. In an overseaming sewing machine, the combination with a stitch-forming mechanism including multiple loop-takers and a needle-bar provided with a concentrically mounted needle co-operating with each of the loop-takers to form stitches, of means for giving to said needle vertical, lateral and oscillatory movements including coacting gear members.

5. In an overseaming sewing machine, the combination with a stitch-forming mecha-

nism including multiple loop-takers, and a
needle-bar provided with a concentrically
mounted needle coöperating with each of the
loop-takers to form stitches, of means for
5 giving to said needle vertical, lateral and os-
cillatory movements including a main shaft
for giving to said needle its vertical move-
ments, a cam carried by said main shaft for
effecting said lateral movements, and coact-
10 ing gear members for effecting said oscil-
latory movements.

6. In an overseaming sewing machine, the
combination with a stitch-forming mecha-
nism including multiple loop-takers, and a
15 needle-bar provided with a concentrically
mounted needle coöperating with each of the
loop-takers to form stitches, of means for
giving to said needle vertical, lateral and
20 oscillatory movements including coacting
gear members, and means for maintaining

said needle-bar in effective relationship with
said gear members.

7. In an overseaming sewing machine, the
combination with a stitch-forming mecha-
nism including multiple loop-takers, a re-
ciprocating needle-bar, and a concentrically
25 mounted needle carried by said bar, said
needle coacting with said loop-takers to
form stitches, of means for giving to said
needle lateral and oscillatory movements in-
30 termediate the different paths of reciproca-
tion of the needle.

In testimony whereof, we have signed our
names to this specification, in the presence
of two subscribing witnesses.
